UNITED STATES PATENT OFFICE.

HENDRIK STUKART, OF LAFORTE, INDIANA, ASSIGNOR TO U. S. SLICING MACHINE COMPANY, OF LAFORTE, INDIANA, A CORPORATION OF ILLINOIS.

SHARPENER FOR SLICING-MACHINES.

1,331,596.

Specification of Letters Patent. Patented Feb. 24, 1920.

Application filed July 10, 1916. Serial No. 103,863.

To all whom it may concern:

Be it known that I, HENDRIK STUKART, a subject of the Queen of Holland, residing at Laporte, in the county of Laporte and State of Indiana, have invented certain new and useful Improvements in Sharpeners for Slicing-Machines, of which the following is a specification:

This invention relates to mechanism for sharpening the slicing knives of machines used for slicing meat, and other material, which is ordinarily cut into thin slices before being dispensed to the trade.

The object of the invention is to provide mechanism of the character named which shall be of improved construction and efficient in operation. The invention is exemplified in the combination and arrangement of parts shown in the accompanying drawings and described in the following specification, and it is more particularly pointed out in the appended claims.

In the drawings, Figure 1 is a vertical sectional view through a portion of a slicing machine showing an embodiment of the present invention applied thereto; Fig. 2 is a vertical sectional view on line 2—2 of Fig. 1; Fig. 3 is a horizontal sectional view on line 3—3 of Fig. 2; and Fig. 4 is a vertical sectional view of a detail of construction taken on line 4—4 of Fig. 3.

In slicing machines now in common use, it is usual to provide a rotary disk knife, having the periphery beveled to form the cutting edge for slicing the material upon which the machine operates. In order that the machine may accurately cut thin slices of uniform thickness from material easily broken, as for example, cooked ham, it is necessary that the beveled periphery of the cutting disk shall be kept very sharp, and the edge kept true and accurate. It has been usual heretofore to provide a rotary grinding disk, having a beveled surface arranged to be spring-pressed against the beveled periphery of the knife. In addition to the grinder for the beveled edge of the knife, it has been usual to provide an auxiliary wheel for removing the bur from the opposite edge of the disk after the main grinding operation has been completed.

These features are still retained in the present invention, but the operation of the main grinding wheel has been radically changed. Heretofore it has been the practice to

mount the cutting knife as accurately as possible when new, and to trust to chance that in subsequent grindings it will retain its original accuracy, the grinding wheel being permitted to move under spring pressure 60 against the entire beveled edge of the cutting knife, regardless of whether the edge remains true or not. It has been found that where this construction is used for some length of time, the knife gradually loses its 65 original accuracy, and the edge begins to wobble, not because of play in the bearings, but because of the fact that the position of the edge itself at various points on the periphery of the knife has shifted, due to 70 the grinding operation. If there should chance to be a portion of the knife that is a little softer than other portions, it is apparent that the sharpening wheel will cut more rapidly on this portion than on others, 75 and if the wheel is uniformly spring-pressed against all portions of the periphery, each sharpening operation will deepen the depression made at this soft portion of the knife, thus causing the edge at this point to 80 recede from the general alinement of the knife. It may also happen that a small piece is broken from the edge of the knife by some means, and when this occurs, under the old construction, the grinder will be 85 pressed into the nick thus formed, and instead of the entire knife being ground to form a new edge which shall be in true alinement, a notch is ground in the knife at the position where the original nick was 90 formed, thus shifting the position of the edge at this point. The ultimate result of such grinding is always to produce a more or less inaccurately alined edge which will produce unevenness in the thickness of the 95 slices which are cut. The present invention, by mechanism which will be described, overcomes this difficulty.

A second defect of the old construction is due to the fact that the rotation of the 100 grinding knife has heretofore been produced by the friction between the grinder and the knife itself. This method of driving, as will be readily seen produces merely a comparatively inefficient rubbing action between 105 the grinder and the disk, instead of a true cutting action, such as is produced where the grinder is positively driven against the edge to be sharpened. A positive drive for the grinding wheel is, therefore, employed in 11

the present invention, with the result that a more efficient sharpening action is procured between the grinder and the edge of the knife.

5 In the figures of the drawings, the numeral 1 designates the frame-work of a slicing machine, having a table top 2, over which the carriage for the material to be sliced is reciprocated to bring the material 10 into position to be operated upon by the slicing knife 3. A drive shaft 4 is rotated in the usual manner by mechanism, not shown, and carries a sprocket wheel 5, driving a sprocket chain 6, which rotates a second sprocket wheel 7, secured to a shaft 8, on which the slicing disk 3 is mounted. By this mechanism, the disk is rotated during the cutting operation. The sprocket wheels and chain are inclosed in a hollow 15 casting 9, which forms a casing for this mechanism, and which is provided with a bearing 10 at its upper end for the shaft 8. Projecting upwardly from the bearing 10, is a pair of abutment or wall members 11, 20 between which a base 12, of a socket member 13, is positioned. Lag screws 14 hold the base 12 in place and project through elongated slots 15, arranged to permit a slight adjustment of the socket member 13 25 30 toward and away from the cutting knife 3. Mounted for vertical adjustment in the socket 13, is an upright 16, which is prevented from rotation in the socket and held in adjusted position by a set screw 17, operating in a slot 18, in the upright 16. At the upper end of the upright 16, is an arcuate bracket 19, provided with bearings 20 and 21 at the upper ends of the two arms thereof respectively. Mounted in the 35 40 45 bearings 20 and 21 for pivotal movement about a horizontal axis, is a hollow casing 22, which is approximately spherical in shape, and which may be formed of two sections in order to facilitate assembling of the mechanism which it contains. A bolt 23 is provided with a square head 24 embedded in a corresponding recess in the casing 22, the bolt being journaled in the bearing 20, as shown in Figs. 2 and 3. The bolt 23 50 55 60 65 is provided with a squared portion 25, on which is mounted an arm 26, having a finger piece 27 at the outer end thereof. A pin 28 projects from the arm 26 on the side opposite the finger piece 27, and co-operates with depressions in an arc-shaped bracket 29, secured to the bearing 20. By this construction, the casing 22 may be rotated to different positions about its horizontal axis, and held in these positions by the pin 28 70 75 80 85 90 95 100 105 110 115 120 125 130 projecting into the depressions in the holding bracket 29. The pin 28 may be spring-pressed, or the arm 26 may be made sufficiently resilient to permit shifting of the pin into and out of the depressions.

65 Journaled in the bearing 21, is a sleeve 30,

on which the casing 22 is mounted, and to which it may be rigidly secured by a set screw 31. As shown in Fig. 3, the sleeve 30 has secured to it within the casing 22, a bracket 32, having horizontally extending arms secured thereto within the casing. The arms of the bracket 32 carry at their extremities alining bearings 34 and 35 respectively. A beveled pinion 36 is journaled in the bearing 34, and a sleeve 37 is mounted in the bearing 35 and is movable longitudinally thereof. The opening in the bearing 35 is enlarged throughout a portion of the length thereof as shown in Fig. 3, to accommodate a coil spring 39, which bears at one end against a shoulder 40 on the bearing 35, and at the other end against a shoulder 41, formed by an enlarged portion 42, of the sleeve 37. The spring 39 normally tends to force the sleeve 37 outwardly, as will be readily understood. A shaft 43 passes through the sleeve 37, and is free to rotate therein. The enlarged portion 42 of the sleeve 37 extends through an opening 45 in the side of the casing 22 adjacent the knife 3, and a grinding wheel 46 is carried by the shaft 43 in a position adjacent the periphery of the knife 3 and on the outside of the casing 22. The portion of the shaft 43 which extends through the pinion 36 is provided with a flattened portion 47 to cause the shaft to rotate with the pinion, but to permit the shaft to move longitudinally relative thereto.

A shaft 48 is journaled in the sleeve 30 and carries a beveled gear 49 at the end thereof, within the casing 22, in position to mesh with the beveled pinion 36. Secured to the opposite end of the shaft, beyond the bearing 21, is a second beveled pinion 50, which meshes with a pinion 51, carried on the upper end of a vertical shaft 52, journaled in an arm 53, which extends laterally from the bracket 19. The lower end of the shaft 52 is journaled in a bearing 54, carried by a laterally extending bracket 55, securing to the casing member 9. The lower end of the shaft is provided with a beveled pinion 56, meshing with a beveled pinion 57, carried on a shaft 58, journaled in a bearing 59, extending through the casing member 9. Secured to the end of the shaft 58, within the casing 9, is a beveled pinion 60, which meshes with a beveled wheel 61, mounted to rotate freely on the drive shaft 4. The gear 61 may be clutched to the shaft 4 by a friction clutch 62, operated by a hand knob 63 and clutch rod 64, arranged to move in an opening 65 in the end of the shaft 4. When the gear 61 is clutched to the shaft 4, and the machine is operated, the grinding wheel 46 will be positively driven through the train of gearing described, the gear ratio being such that the movement of the wheel will be considerably more rapid

than would be imparted to it by simple frictional contact between the grinding wheel and the cutting knife. The direction of rotation of the gear of the grinder 46 is preferably such that the operating portion of the grinder will move toward the edge being sharpened. The vertical position of the grinder, relative to the knife, may be regulated by adjusting the upright 16 in the socket 18, the upright being held in fixed position after it has been adjusted by the set screw 17. In order that this adjustment may not interfere with the operation of the shaft 52, this shaft is provided with an extension coupling 66, as shown in Fig. 2. The grinder 46 is provided with a beveled edge 67, which bears against the beveled portion of the knife 3, as indicated in Fig. 1. In order that the position of the grinding edge of the wheel 46 may be accurately adjusted relative to the edge of the knife, the bracket 32 may be shifted in the casing 22, and held in adjusted position by the set screw 31. The opening 45 through which the sleeve 42 extends is oblong in shape, as shown in Fig. 2, for the purpose of permitting movement of the bracket 32 and the grinding wheel 46 into various adjusted positions relative to the casing 22. The bracket 32 is so shaped that the axis on which the wheel 46 rotates stands at an oblique angle to the plane of the knife 3, in order that the beveled surface 67 may bear properly against the edge of the knife.

The grinder wheel 46 is normally forced outwardly against the cutter 3 by means of the coil spring 39. To hold the grinder away from the knife, when the knife is not being sharpened, the sleeve 37 is provided with a rigidly attached arm 68, on the end of which is mounted a cam roller 69, arranged to bear against the cam surface of a wheel 70 mounted for rotation on a shaft 71, secured to and projecting inwardly from one side of the casing 22. A coil spring 72 is secured to the cam wheel 70 and the shaft 71, and normally tends to rotate the wheel to the right, as viewed in Fig. 3. The wheel is carried by a hub 73, which has a handle or lever 74 secured thereto, arranged to project upwardly through a slot 75 in the casing 22, as shown in Figs. 1 and 2. The lever 74 may be moved in a clockwise direction, as viewed in Fig. 2, against the tension of the spring 72, and secured in two adjusted positions by a sliding detent 76, which co-operates with openings 77 and 78 in the casing 22, which are of greater diameter than the width of the slot 75, and into which the detent 76 may be moved by any well known operating mechanism carried by the handle 74. The cam surface 80, shown in broken lines in Fig. 3, is so shaped that the first result of the movement of the lever 74 to the right, is to permit the wheel 46 to be forced by the spring 39 into contact with the cutter 3. The cam surface 80 is deep enough to permit a somewhat greater movement than would ever be necessary to bring the grinder into contact with the knife to be sharpened, in order to insure contact under all conditions when the lever is moved.

A second cam 81 is secured to the hub 73, on which the cam 70 is mounted, the shape of this cam being shown best in Fig. 4. One end of a lever 82 rests on the periphery of the cam 81, and the lever is pivoted at 83, between two projections 84 extending from the bearing 35, carried on the bracket 32. An opening 86 of greater diameter than the space between the projections 84 extends through the bearing 35 to the sleeve 37. A friction shoe 87 is located in the opening 86, and a coil spring 88 is positioned in the opening between the friction shoe 87 and the short end 89 of the lever 82. During the first part of the movement of the lever 74, and until after the arm 68 has been released by the cam surface 80 to permit the grinder wheel 46 to be moved into contact with the knife 3, the arm 82 bears upon a portion of the cam 81, which is concentric with the shaft 71. After the grinder 46 has moved into contact with the knife 3, and is held in this position by the knife against the tension of the spring 39, the active portion of the cam 81 contacts with the lower surface of the lever 82 and forces the long end of the lever upwardly, thus causing compression of the spring 88 to force the friction shoe 87 against the sleeve 37. In this way, the shoe 87 is held against the sleeve 37 by resilient force sufficient to prevent any further movement of the sleeve 37 in a longitudinal direction. The grinder 46 is thus rigidly locked in position relative to the knife, and is, therefore, not permitted to change its position during the grinding operation. This insures accurate grinding of the knife, with the result that the entire periphery of the knife will be in true alignment when the grinding operation is completed. The parts are so proportioned that the arm 68 will first be released, and the friction shoe 87 subsequently forced into locking contact with the sleeve 37, both operations being completed when the lever has been moved a sufficient distance to cause the detent 76 to register with the opening 77 which marks the first operating position of the lever 74. During further movement of the lever 74 to the right, as shown in Figs. 2, 3 and 4, a second concentric portion of the cam 81 will co-operate with the lever 82, and continue to hold the friction shoe 87 in locking contact with the sleeve 37.

A second grinding wheel 90 is secured to the end of a shaft 91, and held in position on the side of the knife 3, opposite that occupied by the grinder 46. The shaft 91 is

mounted for rotation within a sleeve 92, but constrained to move longitudinally with the sleeve. The sleeve 92 is carried by a bearing cylinder 93, secured to the casing 22, and is 5 free to move longitudinally within the cylinder. A coil spring 94 normally tends to force the sleeve 92 inwardly to draw the grinder 90 against the outer surface of the blade 3. A cam roller 95 is secured to the 10 sleeve 92, and bears against the edge of the cam 70, opposite that against which the roller 69 bears. The cam roller 95 normally holds the grinder 90 away from the blade 3 against the tension of the spring 94. 15 When, however, the cam 70 is moved by the lever 74 past the position in which the lever is held by the opening 77, the roller 95 moves over the cam surface 96 on the wheel 70, and permits the inner surface of the grinder 90 20 to be drawn against the outer portion of the blade 3. While the lever is in this position, the grinder 46 remains locked in its operating position by the cam 81 and the friction shoe 87. The detent 76 may be moved into 25 the opening 78 to retain the parts in this position as long as desired. This need not be more than a sufficient time to permit one or two rotations of the blade 3, since all that the grinder 90 is intended to do, is to remove 30 any bur that may be formed by the grinder 46. Since no actual grinding is desired on the part of the wheel 90, this wheel need not be positively driven, as in the case of the wheel 46, but may depend for its rotation 35 upon the frictional contact between the grinder and the knife.

After a sharpening operation has been completed, the lever 74 is permitted to return to its initial position under the influence 40 of the spring 72, thus moving the grinders 46 and 90 away from the knife 3. In order to further move the grinders out of operative position and away from the knife, the entire casing 22 may be rotated 45 about its horizontal axis by moving the finger piece 27 and the arm 26, to rotate the casing in a counter-clockwise direction, as viewed in Fig. 1. This will move the grinder wheels upwardly away from the knife into 50 a position in which they are held by the pin 28 until it is desired to repeat the sharpening operation.

I claim:-

1. In a slicing machine having a rotary 55 slicing knife, a sharpener for said knife, means for rotating said slicing knife, and separate means for operating said sharpener while in contact with said knife, said separate means being arranged to impart a linear speed to the portion of said sharpener 60 contacting with said knife, differing from the linear speed of the portion of the knife with which it contacts.

2. In a slicing machine having a movable 65 slicing knife, a movable sharpener for said

knife, and separate driving means for imparting simultaneous movements differing in speed to said sharpener and knife while they are in contact with one another and while said knife is in operative position on 70 said machines.

3. In a slicing machine having a rotary slicing knife, a rotary sharpener for said knife, and separate driving means for imparting simultaneous rotation to said sharpener and knife while they are in contact with one another and while said knife is in operative position on said machine, the linear speeds of the contacting portions of said sharpener and knife differing from one another.

4. In a slicing machine having a rotary slicing knife, a sharpener wheel for said knife, and means for simultaneously imparting independent rotation to said sharpener wheel and knife in approximately the same direction while said wheel and knife are in contact with one another and while said knife is in operative position on said machine, the linear movement of the contacting parts of said wheel and knife differing in speed.

5. In a slicing machine, a drive shaft, a slicing knife, means for connecting said shaft with said knife to rotate said knife, a 95 sharpener wheel for said knife, means for connecting said sharpener wheel with said drive shaft to rotate said wheel, and a clutch for connecting and disconnecting said last-named means with said shaft.

6. In a slicing machine, a driving device, a sharpener, means for connecting said driving device with said sharpener for operating said sharpener, said connecting means being arranged to permit adjustment of said 105 sharpener without breaking the driving connection between said sharpener and said driving device.

7. In a slicing machine, a driving device, a sharpener, and extensible transmission 110 mechanism for driving said sharpener from said driving device and for permitting adjustment of said sharpener without breaking the driving connection between said sharpener and said driving device.

8. In a slicing machine having a slicing knife, a sharpener for said knife adjustable relative thereto, and transmission mechanism for imparting power to said sharpener, said transmission mechanism being arranged to permit adjustment of said sharpener relative to said knife without interfering with the transmission of power thereto.

9. In a slicing machine having a rotary 125 slicing knife, a drive shaft, means for connecting said knife with said drive shaft to drive said knife, a sharpener wheel for said knife, and transmission mechanism for imparting movement from said knife to said 130

- sharpener wheel, said transmission mechanism embodying an extensible shaft to permit adjustment of said sharpener relative to said knife.
5. 10. A sharpener for slicing machines comprising a casing, a shaft mounted in bearings inclosed within said casing, a sharpener wheel mounted on said shaft without said casing, and means for driving said shaft for operating said sharpener wheel.
11. In combination, a slicing machine frame, a knife mounted for rotation thereon, a shaft carried by said frame, a casing inclosing said shaft, a sharpener wheel for 15 said knife carried by said shaft, means for adjusting said shaft relative to said casing, means for adjusting said casing relative to said frame, and means for driving said shaft to operate said sharpener wheel to 20 sharpen said knife.
12. In a slicing machine having a slicing knife, a shaft arranged at an oblique angle to the plane of said knife, a casing inclosing said shaft, a sharpener wheel carried by said 25 shaft, means for adjusting said shaft relative to said casing and means for driving said shaft to operate said sharpener wheel.
13. In a slicing machine having a rotary slicing knife, a shaft arranged at an angle 30 to the plane of said knife, a sharpener wheel carried by said shaft, means for rotating said shaft to operate said sharpener wheel, and means for moving said wheel into and out of contact with said knife.
35. 14. In a slicing machine having a slicing knife, a shaft arranged at an oblique angle to the plane of said knife, a sharpener wheel mounted on said shaft, means for rotating said shaft to operate said sharpener wheel, and means for tilting said shaft to move said 40 wheel toward and away from said knife.
45. 15. In a slicing machine having a slicing knife, a shaft arranged at an oblique angle to the plane of said knife, a sharpener wheel for said knife secured to said shaft, means for rotating said shaft to operate said sharpener wheel, means for moving said wheel in the longitudinal direction of said shaft, and means for tilting said shaft to move said 50 wheel.
55. 16. In a slicing machine having a slicing knife, a casing, a shaft mounted within said casing, a sharpener wheel carried by said shaft, and means for changing the position of said shaft relative to said casing to adjust said sharpener wheel relative to said knife.
60. 17. In a slicing machine having a slicing knife, a casing, a shaft mounted within said casing, a sharpener wheel carried by said shaft, means for changing the position of said shaft relative to said casing for adjusting said sharpener wheel relative to said knife, and means for moving said sharpener wheel and casing together relative to said 65 knife.
18. In a slicing machine, a casing, a shaft mounted within said casing, a sharpener wheel carried by said shaft, a drive shaft extending into said casing and connected with said first-mentioned shaft to operate 70 said sharpener wheel, and means for adjusting the position of said first-mentioned shaft relative to said casing.
19. In a slicing machine, a casing mounted for movement about a pivotal axis, a shaft 75 carried by said casing, a sharpener wheel carried by said shaft, and a drive shaft located at the pivotal axis of said casing and connected with said first-mentioned shaft within said casing for operating said sharpener wheel.
20. In a slicing machine, a casing, a bracket mounted within said casing, a shaft journaled within said bracket, means for rotating said shaft, and a sharpener wheel carried by said shaft without said casing.
21. In a slicing machine, a casing mounted for rotation about a pivotal axis, a bracket within said casing and adjustable relative thereto, a shaft journaled in said bracket, a sharpener wheel carried by said shaft, and a drive shaft located at the pivotal axis of said 85 casing for operating said first-mentioned shaft to rotate said sharpener wheel.
22. In a slicing machine having a slicing 90 knife, a sharpener for said knife comprising a casing mounted for movement about a pivotal axis, a bracket within said casing, a shaft journaled at an oblique angle to the plane of said knife, a drive shaft located at the pivotal axis of said casing for operating said first-mentioned shaft, a sharpener wheel carried by said first-mentioned shaft adjacent said slicing knife, and means for moving said casing about its pivotal axis to move 95 said sharpener wheel toward and away from said sharpener wheel.
23. In a slicing machine having a knife, a sharpener for said knife, and means for positively holding said sharpener from moving bodily relative to said knife during a 100 sharpening operation.
24. In a slicing machine, a slicing knife, a sharpener for said knife, and means for preventing movement of said sharpener 105 transversely to the plane of said knife during a sharpening operation.
25. In a slicing machine having a slicing 110 knife, and means for aligning the edge of said knife while said knife is mounted in operating position on a slicing machine.
26. In a slicing machine having a rotary slicing knife, and means for shaping the peripheral portion of said knife to cause the various portions of the edge thereof to travel 115 through the same plane relative to said machine when passing a given angular position.
27. In a slicing machine having a rotary 120 slicing knife, and means for truing the edge 125 of said knife.

- of said knife to cause the various portions of said edge to travel in the same cutting plane when said knife is rotated.
28. In a slicing machine having a rotary slicing knife, a grinder for truing the edge of said knife, and means for preventing said grinder from moving bodily relative to the cutting plane of said knife during a grinding operation.
29. In a slicing machine having a knife for cutting material to be sliced, a sharpener for said knife, means independent of said knife for operating said sharpener, and means for preventing said sharpener from moving bodily relative to said knife during a sharpening operation.
30. In a slicing machine having a rotary slicing knife, a sharpener wheel for said knife, separate means for rotating said knife and sharpener wheel while in contact with one another for sharpening said knife, and means for preventing movement of said sharpener wheel relative to the cutting plane of said knife during a sharpening operation.
31. In a slicing machine having a rotary slicing knife, a sharpener for said knife, means for moving said sharpener toward and away from said knife, and means for locking said sharpener against such movement.
32. In a slicing machine having a rotary slicing knife, a sharpener for said knife, means other than said knife for driving said sharpener, means for moving said sharpener into contact with said knife, and means for locking said sharpener in this position.
33. In a slicing machine having a slicing knife, a sharpener for said knife, resilient means for moving said sharpener into contact with said knife, and means for locking said sharpener in the position thus assumed.
34. In a slicing machine having a rotary slicing knife, a sharpener for said knife, means for adjusting said sharpener relative to the cutting plane of said knife, and means for locking said sharpener in adjusted knife grinding positions and against such movement.
35. In a slicing machine having a slicing knife, a sharpener for said knife, means for resiliently moving said sharpener into contact with said knife where it is held by said knife against the tension of said resilient means, and means for locking said sharpener in the position thus assumed.
36. In a slicing machine having a rotary slicing knife, a grinding wheel for said knife, means for moving said wheel into contact with said knife, means for subsequently locking said wheel in the position thus assumed, and means for rotating said knife while said sharpener is locked in this position to cause said sharpener to true the edge of said knife.
37. In a slicing machine having a rotary slicing knife, a sharpener wheel for said knife, resilient means for moving said wheel into contact with said knife where it is held by said knife against the tension of said resilient means, means for subsequently locking said wheel against moving bodily relative to said knife, and means for rotating said wheel and knife while thus positioned relative to one another to sharpen said knife and to true the edge thereof.
38. In combination, a rotary sharpener for a rotary slicing knife, means for causing said sharpener and knife to contact with one another near the peripheries thereof, and means for driving the contacting portions of said knife and sharpener in the same general direction, said driving means being arranged to impart a more rapid linear movement to the portion of said sharpener contacting with said knife than is imparted to the contacting portion of said knife.
39. In a slicing machine having a rotary slicing knife combination, a drive shaft, means for connecting said knife with said shaft to be driven thereby, a rotary grinder for said knife, a driving train connecting said grinder and said drive shaft, said train including means for breaking the driving connection between said shaft and said grinder, an adjustable support for said grinder, and a driving connection between said grinder and said driving train arranged to maintain operative connection between said grinder and said train independently of the adjustment of said grinder support.
40. In combination, a sharpener for a rotary slicing knife, means for moving said sharpener into contact with said knife, and positive means for preventing movement of said sharpener toward said knife beyond a position fixed by said means.
41. In combination, a grinder for a rotary slicing knife, resilient means for moving said grinder into contact with said knife, positive means for preventing movement of said grinder toward said knife beyond a position fixed by said positive means, and mechanism other than said knife for driving said grinder.
42. In a slicing machine, a sharpener for a rotary slicing knife, means other than said knife for driving said sharpener, and mechanism for moving said sharpener into contact with said knife and for locking said sharpener in position after it has come into engagement with said knife.
- In testimony whereof I have signed my name to this specification on this 7th day of July, A. D. 1916.
- HENDRIK STUKART.
